CONVEYING DEVICE

Gottfried Maurer, Zurich, Switzerland, assignor to the firm A. Müller & Cie. Maschinenfabrik und Eisengiesserei Aktiengesellschaft, Brugg, Switzerland, a joint-stock company of Switzerland

Original application December 13, 1939, Serial No. 309,099. Divided and this application September 9, 1940, Serial No. 356,090. In Switzerland November 3, 1939

10 Claims. (Cl. 198—219)

This application is a division of application Ser. No. 309,099 filed December 13, 1939, and relates to a conveying device comprising opposed groups of bars moving forward and backward and toward and away from one another thereby gripping and carrying forward the goods to be conveyed. It is preferably used for working and dressing wood-pieces, e. g. for treating plywood-plates and veneers.

An object of the invention is to provide suitable driving means connecting the supporting means of the opposed groups of bars and moving the opposed groups toward and away from each other and to control the operation of the driving means by the forward and backward motion of the opposed groups.

In a preferred embodiment these driving means are right and lefthand threaded spindles. Stops on the opposed groups of bars strike, in the course of the forward and backward motion of the groups, against crank arms secured to said spindles, thus rotating these latter.

Another object is to provide slides constituting said supporting means, these slides engaging guides on the machine frame and having raceways on which suitable members, e. g. rollers, mounted on the groups, run forward and backward.

Other objects and features will be apparent as the following description proceeds, reference being had to the accompanying drawings, in which

Fig. 1 is a longitudinal section of an embodiment, taken on line I—I of

Fig. 2, which is a plan view;

Fig. 3 is a front view of this embodiment and

Fig. 4 is a section taken on line I—I of Fig. 2, on an enlarged scale.

The box-shaped standards 70 are held together at the bottom by the struts 71 and at the top by the rods 72 and 73. These standards serve to carry a cam shaft 74 driven by the gear wheel 75 and provided with two pairs of cams 76, 77 displaced in relation to each other, whose manner of action will be shown later on.

Two vertical guide pieces 78 of the same kind, on which slides 79 move up- and downwards, are provided on each of the standards 70. The slides are driven by spindles 80 each with a right handed thread at one end and a left handed thread at the other end. These threads engage those of lateral lugs 81 passing through broad slots provided on the walls of the guide pieces 78. Each of the slides 79 has a horizontal race-way 82, 83 respectively. The race-ways 82 (on the right side in Fig. 3) have plane and the ways 55

83 (on the left side in Fig. 3) have V-shaped guide faces. Between the standards 70 two conveying beds are arranged, which can be displaced in a vertical direction with regard to each other by means of spindles 80. The lower bed consists of two groups of bars 84, 85 and the upper bed of two groups of bars 86, 87. The bars of each group of the upper and lower bed are disposed in such a way that each bar of a group lies between two bars of the other group. The bars of each group are attached to two cross girders, each lying between the raceways 82 and 83. The bars 84 of the lower bed are secured to the cross girders 88, 89 and the bars 85 to the girders 90, 91. In a like manner the bars 86 of the upper bed are mounted on girders 92, 93 and the bars 87 on girders 94, 95.

Rollers 96, 97 of the girders engage the raceways 83, 82 along which the girders are moved to and fro when the cams 76, 77 rotate. In order to allow the groups of bars to be driven by the cams 76, 77, levers 98, 99 are mounted on the shaft 72 with allowance for oscillating and are pressed against the cams 77, 76 with the aid of springs 100, 101 respectively. Bolts 104 of bearings 102, 103 enter slots of the lower end of the levers 98, 99. The bearings 103 are mounted on bars 86 of one group and the bearings 102 on bars 87 of the other group of the upper conveying bed.

Pins 148 and 149 of the outer upper bars engage slots 150, 151 of plates 152 and 153 attached to the lower outer bars. If, therefore, the groups of bars 86, 87 of the upper conveying bed are reciprocatorily moved by means of the cams 76, 77 and springs 101, 100 respectively, these upper groups carry the lower groups along with the help of said pins 148, 149 and plates 152 and 153. From this it follows that lower and upper bars 84, 86 (85, 87 respectively) facing each other move in the same direction at the same time, but the groups 84, 86 and 85, 87, owing to the mutual position of the cams 76, 77 on shaft 74, move in opposite directions to each other. For the purpose of rotating the spindles 80 to and fro at the same angle on each reciprocating movement of the bar groups, each of the lower cross girders 88, 89, 90, 91 comprises two adjustable stops 110, 111 cooperating on each reciprocating movement with a crank arm 112 secured to the lower end of the spindles 80. Owing to the fact that the ends of each spindle are provided with right and left hand threads, this rotation to and fro causes the upper and lower bars of the same group to recede from

or to approach one another to such an extent that the goods to be conveyed and pressed are either released or engaged.

From the foregoing description it follows: The goods to be conveyed enter the machine at the right side of Figure 1. If the cooperating bars of a group, e. g. the bars 85, 87 attached to the cross-girders 90, 94 and 91, 95, coming from the left, have reached the position immediately preceding that where the stops 110 attached to the girders 90, 91 strike against the corresponding crank arms 112, they are still raised from one another and can receive the goods. As soon as these stops 110 strike against the crank levers 112, which happens simultaneously at both ends 15 of all the cross girders of the same group of bars the spindles rotate and the upper and lower bars in question begin to move toward one another. The goods are not wholly gripped till the end of the spindle-rotation, i. e. till the bars 85 and 87 are in their right dead center. This dead center position is shown in Figures 1 and 3 for the cross girders 90, 94 and 91, 95, i. e., for the bars 85, 87. Now the bars 85, 87, together with the goods, move to the left, until the stops 111 attached to the girders 90, 91 drive the spindles with the aid of the corresponding crank arms 112 in the other direction, whereby the bars 85, 87 of the group in question move away from one another. At the end of this spindle-rotation, the upper and lower bars 87 and 85 are in their left dead center which is shown in Fig. 1 but for bars 86 and 84 of the other group. Now the bars 85, 87 have released the goods and in their open position move to the right, and approach one another at the end of said right hand motion as already explained.

The position of the cams 76, 77 in relation to each other is such that the second group, consisting of the bars 84, 86, moves to the right with the bars raised from one another, while the first group with the bars 85, 87 engaging the goods, moves to the left, i. e., the cams 76, 77 are displaced 180° in relation to each other (Figs. 1 and 3). In this way the conveying of the goods is effected.

It is understood that also more than two bar groups might be provided.

While this embodiment of the invention has been illustrated and described in such detail as to enable any one skilled in the art to practise the invention, nevertheless it is to be understood that the invention is not to be limited to any of the details disclosed, but, instead, it will be understood that the invention embraces such embodiments of the broad idea as fall within the scope of the subjoined claims, it being obvious that various changes may be made without departing from the spirit of the invention.

What I claim is:

1. In a conveying device comprising opposed groups of bars, suitable supporting means for said groups, adapted to move toward and away from one another, suitable operating means for said groups whereby two opposed groups are caused to move forward and backward, and right and left hand threaded spindles connecting the supporting means of two opposed groups, said spindles being adapted to be controlled by the forward and backward motion of said two opposed groups and to move said two opposed groups toward and away from each other.

2. In a conveying device comprising opposed groups of bars, a machine frame, guide pieces on said machine frame, slides engaging said guide

pieces, raceways on said slides, members on said groups, adapted to run forward and backward on said raceways, suitable operating means for said groups whereby the opposed groups are caused to move forward and backward, and right and left hand threaded rotatable spindles connecting said slides, said spindles being adapted to be controlled by the forward and backward motion of opposed groups and to move said groups toward and away from each other.

3. In a conveying device comprising opposed groups of bars, a machine frame, guide pieces on said machine frame, slides engaging said guide pieces, raceways on said slides, members on said groups, adapted to run forward and backward on said raceways, suitable operating means for said groups whereby the opposed groups are caused to move forward and backward, right and left hand threaded spindles connecting said slides, said spindles being adapted to rotate and thus to move said groups toward and away from each other, crank arms on said spindles, and stops on said groups, adapted to strike against said crank arms in course of the forward and backward motion of said groups and thus to rotate said spindles.

4. In a conveying device comprising opposed groups of bars, a machine frame, guide pieces on said machine frame, slides engaging said guide pieces, raceways on said slides, rollers on said groups, adapted to run forward and backward on said raceways, suitable operating means for said groups whereby the opposed groups are caused to move forward and backward, and right and left hand threaded rotatable spindles connecting said slides, said spindles being adapted to be controlled by the forward and backward motion of opposed groups and to move said groups toward and away from each other.

5. In a conveying device comprising opposed groups of bars, a machine frame, guide pieces on said machine frame, slides engaging said guide pieces, raceways on said slides, rollers on said groups, adapted to run forward and backward on said raceways, suitable operating means for said groups whereby the opposed groups are caused to move forward and backward, right and left hand threaded spindles connecting said slides, said spindles being adapted to rotate and thus to move said groups toward and away from each other, crank arms on said spindles, and stops on said groups, adapted to strike against said crank arms in the course of the forward and backward motion of said groups and thus to rotate said spindles.

6. In a conveying device comprising opposed groups of bars, suitable supporting means for said groups, adapted to move toward and away from one another, a cam disk adapted to move opposed groups forward and backward, and suitable driving means connecting the supporting means of opposed groups, said driving means being adapted to be controlled by the forward and backward motion of opposed groups and to move said opposed groups toward and away from each other.

7. In a conveying device comprising opposed groups of bars, suitable supporting means for said groups, adapted to move toward and away from one another, a cam disk adapted to move opposed groups forward and backward, and right and left hand threaded spindles connecting the supporting means of two opposed groups, said spindles being adapted to be controlled by the forward and backward motion of opposed groups

and to move said opposed groups toward and away from each other.

8. In a conveying device comprising opposed groups of bars, a machine frame, guide pieces on said machine frame, slides engaging said guide pieces, raceways on said slides, members on said groups, adapted to run forward and backward on said raceways, a rocking lever mounted on said machine frame and pivotally connected with one of said groups, a cam disk engaging said rocking lever, adapted to move opposed groups forward and backward, and right and left hand threaded rotatable spindles connecting said slides, said spindles being adapted to be controlled by the forward and backward motion of opposed groups and to move said groups toward and away from each other.

9. In a conveying device comprising two pairs of opposed groups of bars, a machine frame, guide pieces on said machine frame, slides engaging said guide pieces, raceways on said slides, rollers on the groups of each pair, adapted to run forward and backward on said raceways, two rocking levers mounted on said machine frame and each pivotally connected to one group of a pair, two cam disks engaging said rocking

levers and being displaced in relation to each other, adapted to move the two pairs of groups forward and backward with a mutual phase displacement, and right and left hand threaded spindles connecting said slides, said spindles being adapted to rotate and thus to move opposed groups toward and away from each other, crank arms on said spindles, and stops on said groups, adapted to strike against said crank arms in the course of the forward and backward motion of said groups and thus to rotate said spindles.

10. In a conveying device comprising opposed groups of bars, the bars lying side by side at a distance from one another which is smaller than the width of each bar, suitable supporting means for said groups, adapted to move toward and away from one another, suitable operating means for said groups whereby two opposed groups are caused to move forward and backward, and right and left hand threaded spindles connecting the supporting means of two opposed groups, said spindles being adapted to be controlled by the forward and backward motion of said two opposed groups and to move said two opposed groups toward and away from each other.

GOTTFRIED MAURER.
